US00D778925S

(12) **United States Design Patent** (10) Patent No.: **US D778,925 S**
 Lee et al. (45) Date of Patent: ** *Feb. 14, 2017

(54) **TV RECEIVER WITH GRAPHICAL USER INTERFACE**

(71) Applicant: **LG ELECTRONICS INC.**, Seoul (KR)

(72) Inventors: **Kunsik Lee**, Seoul (KR); **Uniyoung Kim**, Seoul (KR); **Goeun Lee**, Seoul (KR); **Ryunghwa Rhee**, Seoul (KR)

(73) Assignee: **LG ELECTRONICS INC.**, Seoul (KR)

(*) Notice: This patent is subject to a terminal disclaimer.

(**) Term: **15 Years**

(21) Appl. No.: **29/537,396**

(22) Filed: **Aug. 25, 2015**

(30) **Foreign Application Priority Data**

Feb. 25, 2015 (KR) 30-2015-0009568

(51) **LOC (10) Cl.** **14-04**

(57) **CLAIM**

The ornamental design for a TV receiver with graphical user interface, as shown and described.

DESCRIPTION

The FIGURE is a front view of a TV receiver with graphical user interface showing our new design.

The broken lines showing text, portions of the graphical user interface, and the TV receiver form no part of the claimed design.

1 Claim, 1 Drawing Sheet
